UNITED STATES PATENT OFFICE.

CHARLES D. WOOD, OF CENTRAL FALLS, RHODE ISLAND.

CORSET-SPRING.

SPECIFICATION forming part of Letters Patent No. 748,830, dated January 5, 1904.

Application filed October 23, 1903. Serial No. 178,296. (No model.)

To all whom it may concern:

Be it known that I, CHARLES D. WOOD, of Central Falls, in the county of Providence and State of Rhode Island, have invented certain new and useful Improvements in Corset-Springs, of which the following is a specification.

This invention has for its object to provide a corset-spring of superior strength, resiliency, and durability and one which will have no liability to become permanently bent or distorted by the use to which it is subjected.

The invention consists in the improvements which I will now proceed to describe and claim.

Of the accompanying drawings, forming a part of this specification, Figure 1 represents a side elevation of a corset-spring embodying my invention. Fig. 2 represents a section on line 2 2 of Fig. 1 on an enlarged scale. Fig. 3 represents a side view showing a modification. Figs. 4 and 5 represent enlarged sections on lines 4 4 and 5 5 of Fig. 3.

The same reference characters indicate the same parts in all the figures.

In carrying out my invention I assemble a series of lengths or members *a a*, of wire, which is preferably composed of steel and is of the quality usually known as "piano-wire," the length of each member *a* being substantially equal to the length of the spring to be produced. These members *a* are placed side by side in contact with each other, their relative arrangement being such that when united, as hereinafter described, they form a spring which has substantially flat sides and is relatively thin—in other words, a spring having the same general proportions as an ordinary sheet-metal corset-spring. The members thus assembled are treated with a material or composition which forms a coating or film *b*, adhering closely to the surfaces of the wires and uniting the wires firmly together without materially increasing the width or thickness of the spring as a whole. The said binding material may be solder, applied to the assembled wires in such manner as to fill or partially fill the grooves formed

by the meeting surfaces of the wires, the coating being preferably so thin that the shape of the wires will show through it, giving the sides of the spring a corrugated appearance. I prefer to extend the said coating over the entire surface of the series of members—that is to say, from end to end and entirely across the same. The wires thus united collectively form an extremely strong, resilient, and durable spring which is in point of strength and resilience much superior to an ordinary sheet-metal spring, owing to the fact that greater strength and a much more effective temper can be imparted to a piece of steel wire than to the corresponding cross-sectional area of a piece of sheet metal. Hence by assembling a series of wire members and uniting the same as described I utilize the above-recited advantages of wire over sheet metal and produce a spring which does not necessarily differ in its proportions and general appearance from the ordinary sheet-metal spring.

I do not limit myself to a spring characterized by the fact that the binding-coating which unites the wires extends the entire length of the spring. In Fig. 3 I show a modification in which the binding-coating is applied to limited areas or sections of the spring, the wire members *a* being bare or exposed at other parts. In Fig. 4 I show a cross-section of one of the portions of the spring, in which the wires are united by the coating *b*, while in Fig. 5 I show a section of one of the portions in which the wires are not united.

While solder is the best material for the binding-coating of which I am at present aware, I do not limit myself thereto, as a thin coating of celluloid, rubber, or vulcanized fiber may be used with reasonably satisfactory results. When solder is used, its surface may be coated with paint or other material to prevent the solder from tarnishing white fabrics and to exclude moisture from the wires.

I desire to emphasize the fact that by my method of uniting the wires I avoid objectionable enlargements or protuberances, such

as are caused by the bands, clips, and clamps heretofore proposed for uniting wires for corset-springs.

I claim—

- 5 A corset-spring comprising a series of parallel wire members laid side by side, and a binding coating or film adhering to and uniting the wires.

In testimony whereof I have affixed my signature in presence of two witnesses.

CHARLES D. WOOD.
